United States Patent Office.

ABRAHAM KIPP, JR., OF SING SING, NEW YORK.

Letters Patent No. 81,649, dated September 1, 1868.

IMPROVEMENT IN STEAM AND FIRE-REGULATORS.

The Schedule referred to in these Letters Patent and making part of the same.

TO ALL WHOM IT MAY CONCERN:

Be it known that I, ABRAHAM KIPP, Jr., of Sing Sing, in the county of Westchester, and State of New York, have invented a new and improved Steam-Pressure and Fire-Regulator; and I do hereby declare that the following is a full, clear, and exact description thereof, which will enable others skilled in the art to make and use the same, reference being had to the accompanying drawing, forming a part of this specification.

This invention relates to a new and improved apparatus or device for regulating the pressure of steam in boilers by automatically controlling the fires thereof; and it consists in devices connected with a damper, and communicating with the steam-boiler, as hereinafter fully shown and described, whereby an excess of steam-pressure in the boiler is reduced, by the action of the steam from the boiler upon the mechanism employed, in such a manner as to partially close the damper, and check the draught of the fire, and when the pressure is below the standard required, the mechanism made to open the damper, and thereby increase the draught of the fire.

The accompanying drawing represents a side sectional view of my invention.

A represents a chamber, which communicates with a steam-boiler by means of a pipe, B, and C C' are two compartments in said chamber, each of which is provided at one side with an elastic disk, D, both of which are attached to a sliding arm, E, as shown at a a.

F is an ordinary slide-valve, the exhaust-port, b, of which, is shown by dotted lines, and c c' are the ports which lead respectively to the compartments C C'.

This valve F works in a suitable box, G, which is fitted in a dome, H, in the chamber A, with which dome the steam-pipe B communicates.

The box G is provided with suitable apertures, through which steam is admitted into the ports c c' in box G, as the movement of the valve F will admit.

This arrangement of the valve F and its ports c c' is precisely the same as the ordinary slide-valve of a reciprocating steam-engine, and the dome H corresponds to an ordinary steam-chest. These parts and their operation are so well known to every engineer that a prolix description of them is not deemed necessary.

The valve F is provided with a stem, I, which is fitted into a box, J, the latter communicating at its upper end with the dome H, when the valve F is not down upon it.

The lower end of the valve is connected to an elastic disk, K, which has a pendant, L, extending down below the chamber A, and bearing upon one end of a beam, M, which has knife-edges a x, resting in V-shaped bearings, and on which beam an adjustable ball or weight, N, is placed. This beam and weight correspond to an ordinary scale-beam and weight.

O is a bent or right-angular lever, having its fulcrum at d, and its lower and shorter arm, e, extending within a recess, f, in the beam M.

The upper and longer arm g of this lever is connected to the fire-damper in any suitable way.

The operation is as follows:

The steam from the boiler passes into dome H, and thence into box J, and acts upon the elastic disk K, with a pressure due to that in the boiler, the pressure upon K being transmitted to the inner end of the beam M, which pressure may be resisted in a greater or less degree by the position of the weight N on M.

Suppose, for instance, that a pressure of twenty pounds to the inch be required in the boiler, the weight N may be so adjusted or placed on the beam that the inner end of the latter cannot be forced down until the pressure on K exceeds that, and when this excess of pressure occurs, the forcing down of the inner end of the beam M moves the valve F, so that steam will be admitted into the compartment C', and the steam in C allowed to exhaust through the port b, and the elastic disk D of C' will be pressed outward, and the disk D of C drawn inward, the arm E being thereby moved in the direction of arrow 1, and the arm g of lever O moved in the direction of arrow 2, and the fire-damper turned so as to check the draught of the fire, the cooling down of which reduces the steam-pressure in boiler.

When the steam-pressure in boiler gets below the required standard of twenty pounds to the inch, the weight on beam M will raise the disk X and valve F, so that the part *c'* will be brought in communication with the exhaust-port *b*, while steam will be admitted into the port *c* of the compartment C, and steam exhausted from C', the result of which is the movement of slide F in the direction indicated by arrow 3, and the movement of the arm *g* of lever O in the direction indicated by arrow 4, and the adjustment of the fire-damper, so as to increase the draught of the fire, and the pressure of steam in the boiler.

The beam M may be provided with set-screws, (shown in red,) so as to limit the sweep of the lever O, and thereby control the extent of the movement of the damper, as circumstances may require.

Having thus described my invention, what I claim as new, and desire to secure by Letters Patent, is—

The slide-valve F, in connection with the elastic disks D D K, compartments C C' in chamber A, arm E, and beam M, and the lever O, or its equivalent, all arranged to operate in connection with a fire-damper, substantially in the manner as and for the purpose set forth.

The above specification of my invention signed by me, this 26th day of May, 1868.

A. KIPP, JR.
